[57] CLAIM

The ornamental design for a combined guiro and shaker, substantially as shown and described.

DESCRIPTION

FIG. 1 is a front and top perspective view of a combined guiro and shaker showing my new design;

FIG. 2 is a bottom and rear perspective view, the continuous knurling on the cylindrical portion being shown partially due to light reflection;

FIG. 3 is a front elevational view;

FIG. 4 is a rear elevational view; and

FIG. 5 is a sectional view taken along line 5—5 in FIG. 1.
